UNITED STATES PATENT OFFICE.

JOHN WATERHOUSE, OF NEW YORK, N. Y.

RAILWAY-BUMPER.

SPECIFICATION forming part of Letters Patent No. 402,790, dated May 7, 1889.

Application filed November 21, 1888. Serial No. 291,513. (No model.)

To all whom it may concern:

Be it known that I, JOHN WATERHOUSE, a citizen of the United States, residing at the city of New York, in the county and State of New York, have invented a new and useful Railway-Bumper, of which the following is a specification.

My invention relates to improvements in railway-bumpers.

- 10 The object of my invention is to construct a tipping-bumper between track-rails at such points in the main line of a railway as will protect a train from running into an open draw-bridge or colliding with another train at a railway-crossing, the bumper to be raised and lowered by mechanism attached to a danger-signal, or so attached to the mechanism of a draw-bridge that when it is opened the bumper will be raised and when the bridge is closed the bumper will be lowered and fastened in place, so that a train may pass safely over it. It is also designed to be used in a track-yard where tracks enter a building, and where it is desirable to store cars or engines in front of the building without endangering the closed doors thereof; and when desirable to run cars or engines into the building the bumper may be tipped down and fastened in place and the cars or engine run over it.
- 30 The bumper may be operated by suitable mechanism or by the operator.

Figure 1 shows the plan view of the bumper; Fig. 2, a side view; Fig. 3, an end view; Figs. 4 and 5, enlarged views of slotted plates, spring, and spring-box; Fig. 6, a view of the foot-latch by which the bumper is secured in a horizontal position.

Two track-stringers, *aa*, are framed together and laid upon the wall of a pit and the rails secured to them with their proper gage, the bumper to be preferably made of strong timbers bolted together and capped at the upper end with a strong timber-cap or cross-piece, *b*, the lower end of the bumper to be framed into a foot-casting, *c*, and securely bolted to it. The casting serves to protect the lower end of the bumper in case the bumper is struck by a car or engine, and also to give the desired tipping-weight to the bumper.

50 This weight, which will be adjusted by pouring molten lead in receptacles left in the cast-

ing for that purpose, should be sufficient to tip the bumper easily into the position shown in Fig. 2.

d d are rubber buffers which receive the impact of the train. The force of the impact is resolved into an upward tensile strain in the eye-bars *e e* and a downward thrust through the abutment of bumper to the heavy masonry or timber or iron suspension-bars *60* built to receive it.

The slotted plates *f f* and the spring-box and slotted plate *g g*, containing a coil-spring, are intended to keep the pivot-bar *h* pressed to the front, so that the lower end of the bumper will swing clear of the masonry, and when the bumper does receive a blow the pivot-bar can slide along the slots in *f* and *g*, compressing the spring without danger of being bent.

The eye-bars *e e* are arranged on the side *70* of the bumper and inside of the track-stringers, the two sets being connected by bars that extend from one to the other, as shown in Fig. 3. By moving the middle pin-bar inwardly and at the same time pressing down *75* on the head of the bumper the bumper can be forced down until the top of it is level with the top of the track-stringer, in which position the latch *i*, Figs. 1, 3, and 6, will catch the lower pin-bar and hold the bumper *80* securely down so that the track will be unobstructed and a train can pass over it.

The dotted lines in Fig. 2 show the position of the eye-bars when the bumper is down. By pressing the foot on the lever-arm of the *85* foot-latch the bumper will be released, and the superior weight at the other end will cause the bumper to come up into position shown in Fig. 2. A lug fastened to the inner face of the track-stringer prevents the eye-bars from going outwardly beyond the straight line and keeps them on their centers.

What I claim as my invention, and desire to secure by Letters Patent of the United States, is—

1. A stopping device for railroad cars and engines, consisting of a bumper pivoted in such relation to the rails of a railroad-track that it can be made to occupy a horizontal position beneath the level of the tracks, or *100* tilted to an inclined position so that the upper end will engage the platform or some portion

of the main body of the car or engine, substantially as described.

2. A stopping device for railroad cars or engines, consisting of a bumper pivoted intermediate its ends between the rails of a railroad-track, and an abutment below the track to engage the lower end of the bumper when tilted into operative position to sustain the shock or blow upon the bumper, substantially as described.

3. A stopping device for railroad cars or engines, consisting of a bumper having a pivotal sliding support between the rails of a railroad-track, and an abutment below the track to engage the lower end of the bumper when tilted into operative position to sustain the shock or blow upon the bumper, substantially as described.

4. A stopping device for railroad cars or engines, consisting of a bumper located between the rails of a railroad-track, pivotally mounted in elongated or slotted bearings, a spring bearing upon the rear of the pivot, and an abutment below the track to engage the lower end of the bumper when tilted into operative position to sustain the shock or blow upon the bumper, substantially as described.

5. A stopping device for railroad cars or engines, consisting of a bumper pivoted intermediate its ends between the rails of a railroad-track, a stop for the upwardly-moving

end of the bumper, and an abutment below the track to engage the lower end of the bumper when tilted into operative position to sustain the shock or blow upon the bumper, substantially as described.

6. A stopping device for railroad cars or engines, consisting of a bumper pivoted intermediate its ends between the rails of a railroad-track, eye-bars limiting the movement of said bumper, an abutment below the track to engage the lower end of the bumper when tilted into operative position to sustain the shock or blow upon the bumper, and a foot-latch to hold the bumper in a horizontal position, substantially as described.

7. A stopping device for railroad cars or engines, consisting of a bumper pivoted intermediate its ends between the rails of a railroad-track, and provided with an elastic cushion, a pair of eye-bars limiting the movement of said bumper, a transverse bar connecting the eye-bars, and an abutment below the track to engage the lower end of the bumper when tilted into operative position to sustain the shock or blow upon the bumper, substantially as described.

JOHN WATERHOUSE.
